[57] CLAIM

The ornamental design for an orthodontic bracket, as shown and described.

DESCRIPTION

FIG. 1 is a side elevational view of an orthodontic bracket showing my new design, the other side being a mirror image;

FIG. 2 is a top plan view thereof;

FIG. 3 is a front elevational view thereof;

FIG. 4 is a bottom plan view thereof;

FIG. 5 is a rear elevational view thereof;

FIG. 6 is a perspective view thereof;
FIG. 7 is a side elevational view of a second embodiment thereof, the second embodiment is shown with a color indicator strip;

FIG. 8 is a top plan view thereof;

FIG. 9 is a front elevational view thereof;

FIG. 10 is a bottom plan view thereof;

FIG. 11 is a rear elevational view thereof; and

FIG. 12 is a perspective view thereof.

*Fig. 4.**Fig. 1.**Fig. 2.**Fig. 5.**Fig. 3.**Fig. 10.**Fig. 7.**Fig. 8.**Fig. 11.**Fig. 9.**Fig. 6.**Fig. 12.*
